UNITED STATES PATENT OFFICE.

HOWARD RICHMOND, OF PROVIDENCE, RHODE ISLAND.

APPARATUS FOR DYEING, SCOURING, BLEACHING, AND OTHERWISE TREATING YARN IN COPS.

SPECIFICATION forming part of Letters Patent No. 372,768, dated November 8, 1887.

Application filed August 30, 1887. Serial No. 249,252. (No model.)

To all whom it may concern:

Be it known that I, HOWARD RICHMOND, a citizen of the United States, residing in the city of Providence, county of Providence, and State of Rhode Island, have invented certain Improvements in Apparatus for Dyeing, Scouring, Bleaching, and Otherwise Treating Yarn in Cops, of which the following is a specification.

10 My invention is of general applicability in dyeing, mordanting, bleaching, steaming, scouring, washing, drying, or otherwise treating yarns of cotton, silk, wool, worsted, or other animal or vegetable fiber, in the form of 15 cops, or in kindred compact forms, by either sucking or forcing liquid dyes, or other liquids used in dyeing, mordanting, bleaching, scouring, steaming, or otherwise treating the cops, through the cops when mounted upon hollow 20 perforated tubes, skewers, or injection spindles, which extend respectively through the cops and render every portion of each cop subject to the action of said liquids.

The foregoing operations broadly as such, 25 and as separately conducted in the same or in different machines, are not novel with me, and attempts have heretofore been made, thereby, to practically dye, bleach, and otherwise treat, cotton and other yarns in cop and other compact forms. So far, however, as my knowledge 30 extends, the practice has never been practically or successfully conducted upon a commercial scale, until the date of an invention made by one August Graemiger, a citizen of 35 the Republic of Switzerland, application for patent for which was filed in the United States Patent Office upon April 14th, 1887, and upon which application Letters Patent of the United States No. 368,715, were granted 40 upon the 23d day of August, 1887, to which Letters Patent reference is to be made.

My present invention having the same objects and purposes as, and being an improvement upon, the aforesaid invention of the said 45 Graemiger, it is essential for an accurate understanding of the features of distinction, that the objects, purposes, and salient characteristics of Graemiger's invention aforesaid should be briefly stated.

50 The object of Graemiger's invention, which is of general applicability for dyeing, bleaching, scouring, mordanting, drying, and other-

wise treating yarns of various kinds in cop and other compact forms, is the provision of means whereby all of the cops composing any given series or succession, regular or irregular, of cops or of tiers or groups of cops, may, in the selected series or succession,—as to each cop, tier or group, successively, but as to the entire series or succession of given cops, tiers, 60 or groups, collectively,—be contemporaneously or simultaneously subjected each to its appropriate step of the contemporaneously-conducted successive steps composing the selected process, of any one of which processes, 65 however, continuity of operation in a greater or a less degree, is the especial desideratum and the salient characteristic.

To the foregoing ends the said Graemiger's 70 said invention embraces apparatus having the capacity for performing or carrying out any one of several cognate processes or methods of treatment of yarn in cops or kindred compact forms, and apparatus, moreover, so constituted as to be readily convertible into, or applicable 75 for use as, any one of several cognate yet distinct devices, respectively susceptible of the performance of a particular kind of work, that is to say of the practice of some one of the said several cognate processes, hereinafter mentioned, all of which, as processes or modes of treatment, are novel with Graemiger.

Broadly stated, Graemiger's aforesaid invention, so far as processes are concerned, as applied to dyeing, mordanting, bleaching, scouring, steaming, washing, or otherwise similarly treating by the impregnation of liquids, yarn in cops, comprehends, first, the contemporaneous but distributive subjection of the cops composing a series, each in turn to its appropriate step 85 of the following contemporaneously-conducted successive steps or operations, namely: first, saturation or impregnation by sucking or forcing the selected liquids through given cops; and, second, substitution of fresh cops to be 90 charged for given charged cops.

Similarly, also, Graemiger's invention, as applied to the operations of impregnation above mentioned, comprehends, second, the subjection of the cops in the manner above 100 stated, to the following successive steps or operations: first, saturation or impregnation by sucking or forcing the selected liquid through given cops; second, liquid-exhaustion by fore-

ing or sucking air or other suitable fluid through given charged cops; and, third, substitution of cops to be charged and liquid-exhausted for given charged and liquid-exhausted 5 cops.

Similarly, again, Graemiger's invention as applied to exhausting surplus liquid from charged cops, comprehends, third, the subjection of cops, in the manner above stated, 10 to the following successive steps or operations: first, liquid-exhaustion by forcing or sucking air or other suitable fluid through the cops; second, substitution of cops to be liquid-exhausted for given liquid-exhausted cops. 15 Similarly, again, as applied to operations of dyeing with easily oxidizable liquid dyes, Graemiger's invention comprehends, fourth and fifth, the subjection of the cops in the manner above stated with reference to the first 20 two operations which involve impregnation with liquids,—and in connection either with the two steps of saturation and substitution which are involved in the practice of the first of his foregoing processes, or else in connection with the three steps of saturation, liquid-exhaustion, and substitution which are involved in the second of his foregoing processes,—to a preliminary step of air-exhaustion before saturation or impregnation proper, by 25 sucking or forcing air from out given cops to be charged or saturated.

Graemiger's invention further comprehends apparatus for conveniently effectuating the five several processes which respectively 30 side in the practice of the foregoing respectively recited connected steps or operations, the salient characteristic of which is that it is a rotary apparatus the cop carrier of which rotates referably to a fixed tank and the mouths 35 of certain conduits.

In order that the apparatus which Graemiger devised for the purpose of carrying into operation any one of the above mentioned processes or methods of treatment may be understood, 40 as it is important that it should be understood in order that the distinctions between it and my apparatus, which is designed to effectuate the same processes or methods of treatment, may become apparent,—it is proper to state briefly 45 that Graemiger's machine comprehends: first, a fixed tank, vat, or other recipient, for containing a given quantity of liquid coloring matter or other preferred liquid, and for subserving the purposes of a framework to the 50 machine as an entirety; second, a carrier body which, referably to the fixed tank and the rotating cop carrier, is simply a fixed device conveniently subserving the double purpose, first, of being a fixed body with reference to 55 which the cop carrier has rotary movement, and, second, of being a body containing or embodying, or of being a supporting device serving conveniently to present to the perforations in the cop carrier, the mouths or chambers of 60 the conduits; third, a rotatable cop carrier, or 65 device which carries the cops, which is per-

forated referably to the points of and means for attachment of said cops, and has such rotary movement referably to the carrier body and to the tank that its perforations are in pre- 70 determined continuing sequence placed in communication, preferably through perforated injection spindles, with the axial apertures of the cops on the one hand and with the conduit mouths on the other; fourth, a charging conduit in exterior communication with a suction or pressure pump, and interiorly or as to its mouth, conveniently through the intermediation of the carrier body, in communication for the time being with given perforations in the 80 cop carrier; fifth, a liquid-exhausting conduit in exterior communication with a suction or pressure pump, and interiorly or as to its mouth, conveniently also through the intermediation of the carrier body, in communication 85 for the time being with other given perforations in the cop carrier; sixth, an air-exhausting conduit in exterior communication with a suction or pressure pump, and interiorly or as to its mouth, conveniently also through the intermediation of the carrier body, in communication 90 for the time being with other given perforations in the cop carrier.

Graemiger's machine also comprehends the employment of a dead face or blank space 95 formed upon or embodied in the carrier body, which, however, as a specific device, I prefer not to employ.

Of the foregoing apparatus of Graemiger, the tank, the perforated cop carrier, the charging conduit, the liquid-exhausting conduit, the air-exhausting conduit, and,—as a device of convenience merely, for the purpose of conveniently presenting to given perforations of the cop carrier the mouths of said conduits, 100 and as a device, moreover, with reference to which the cop carrier is conveniently arranged to rotate,—the carrier body, are the vital members, or instrumentalities.

In order to understand the operation of the 110 said Graemiger apparatus, it is sufficient to add that the cop carrier rotates relatively to the tank and the carrier body in such manner as, during a part of its rotation, to occasion the immersion in liquid in the tank of cops carried by it, and also, during a further part of its rotation, the presentation of its perforations with reference to which the cops are secured to it, to the mouths of the conduits. 115

The machine which I have invented, and 120 which is represented in the accompanying drawings, is to be contradistinguished from the Graemiger machine referred to essentially in the fact that its cop carrier is of such construction and general organization as to be 125 adapted to be vibrated, oscillated, rocked, or see-sawed, as opposed to being rotated or moved in a circular plane.

My machine which, as stated, equally with Graemiger's, is adapted to effectuate the process which comprises charging and substitution,—or the process which comprises charg- 130

ing, liquid-exhaustion, and substitution,—or the process which comprises liquid exhaustion and substitution,—or the process which comprises air-exhaustion, dyeing, and substitution, or the process which comprises air-exhaustion, dyeing, liquid-exhaustion, and substitution,—is of the following construction, and comprehends all of the elements which are necessary to the conduct or practice of any one of the foregoing processes,—and consequently of that one which involves the greatest number of steps,—although, as is hereinafter explained, in the practice of such of the processes as involve the lesser number of steps, certain of the elements of the said apparatus are inert or for the time being thrown out of action.

Apparatus conveniently embodying my invention, and adapted to effectuate the separate practice of any one, and, consequently of all, of the processes invented by Graemiger and hereinbefore referred to, is represented in the accompanying drawings and described in this specification, the particular subject matter 25 claimed as novel being hereinafter definitely specified.

In the drawings, Figure 1 is a top plan view of a convenient and cheap form of the entire apparatus. Fig. 2 a face elevational view of the same, sectional in planes of the dotted line O—O of Fig. 1, and sight being taken in the direction of the arrows upon said line. Fig. 3 is an end elevational view of the apparatus represented in Figs. 1 and 2, section being supposed 35 in planes of the dotted line x—x of Fig. 2, and sight being taken in the direction of the arrows upon said line. Fig. 4 is a face elevational view of the carrier body detached from the tank and Fig. 5 is a longitudinal central section view of the cop carrier, in the plane of the dotted line y—y of Fig. 2, and sight being taken in the direction of the arrows upon said line. Figs. 6, 7, 8, 9, and 10 represent a machine embodying a modified form of cop carrier. Figs. 6, 7, and 8 correspond essentially 45 to Figs. 1, 2, and 3; Fig. 9 corresponds to Fig. 4, and Fig. 10 is a plan of the modified form of cop carrier.

Similar letters of reference indicate corresponding parts.

Referring now to Figs. 1 to 5 inclusive, of the drawings, A is a tank or fixed receiving vessel, preferably of such form and strength as to itself constitute or act as the frame-work 55 of the entire apparatus, that is to say as a frame-work with reference to which the cop carrier has vibratory movement and the carrier body and conduits are fixed.

B is what I term the carrier body, it being, 60 referably to the fixed tank and vibratory cop carrier, simply a fixed device conveniently subserving the double purpose, first, of being a fixed body with reference to which the cop carrier vibrates or rocks, and, second, of being 65 a body containing or embodying, or of being a supporting device serving conveniently to

present the wing-orifices of and thereby to the perforations in the cop carrier, the mouths or chambers of the active conduits. The carrier body is preferably a casting of the 70 form shown in Fig. 4, the front face of which, or carrier body proper, is a flat circular plane conveniently surrounded by a flanged rim b, from which projects a cylindriform axial stud or gudgeon b^x upon which the cop carrier is 75 fulcrumed for its vibratory movement. This carrier body is supported in a vertical or approximately vertical plane against the rear wall of the tank in any preferred manner, but conveniently by body tubes b⁰ b¹ and b² b³, cast 80 integral with or applied to it, and being in effect respectively continuations of the respective conduits the inner extremities of which are conveniently screwed into them. For a further convenience of application, these 85 body tubes are connected or stayed by a flat web or base b⁵, preferably cast integral with them and adapted to be bolted to the rear wall of the tank. The body tube b⁰ and the body tube b¹ are each, as shown in the drawings, 90 conveniently extended, oblong, or made of considerable length, while the body tubes b² and b³ are small and cylindric.

D is a charging conduit, preferably fixedly connected with the tank by being passed 95 through an aperture in its rear wall, and threaded into, or otherwise permanently and integrally connected with, the body tube b⁰, as shown in the drawings. This charging conduit leads to, or is exteriorly in direct communication with, a suction or pressure pump of any preferred character, which is adapted either to suck or to force any desired liquid through said conduit, for the saturation, impregnation, or charging of given cops.

E is a liquid-exhausting conduit, preferably also fixedly connected with the tank by being passed through an aperture in its rear wall and threaded into, or otherwise permanently and interiorly connected with, the body tube b¹. 100 This liquid-exhausting conduit leads to, or is exteriorly in direct communication with, a suction or pressure pump of any preferred character, which is adapted either to suck or to force air, or other fluid employed as a liquid-exhausting medium, through said liquid-exhausting conduit.

I have not represented in the drawings the pumps referred to, for the reason that it is not necessary to an understanding of the invention, 110 the pumps being simply, as stated, of any preferred and well known character, and there being no connections other than those which a competent mechanic would naturally employ.

The flanged disk which constitutes the carrier body proper, has cut through its substance certain slots, holes, orifices, or other openings, preferably formed in its casting, which open respectively into the respective body tubes, and constitute circumferentially distributed 120 chambers, depressions, or compartments, each independent of the other.

The principal chambers in the carrier body represented are the charging chamber *d* and the liquid-exhausting chamber *e*,—the said chambers being the terminal portions or mouths 5 respectively of the charging conduit and of the liquid-exhausting conduit.

The charging chamber and the liquid-exhausting chamber are each in form oblong horizontal slots, respectively backed by the respective body tubes *b*² and *b*³, disposed parallel with each other, and each arranged to centrally bisect the vertical diameter of the carrier body, and to be located at equal radial distances from the center of said body, the one near the upper 15 and the other near the lower portion of its circumference. The charging chamber, is, in the mounting of the carrier body, the chamber lowermost within the tank, while the liquid-exhausting chamber is the uppermost. *E*² *E*³ are air-exhausting chambers, being each a preferably circular small opening through the front face and substance of the carrier body, in communication respectively with the body tubes *b*² *b*³. These chambers are located in the line 20 of the horizontal diameter of the carrier body, at equal opposite radial distances from its center, and in the neighborhood of its circumference. These chambers, being respectively laterally intermediate between the charging and 25 the liquid-exhausting chambers are respectively, conveniently through the intermediation of their respective body tubes *b*² *b*³, in communication with air-exhausting conduits *e*² *e*³ leading to and exteriorly in communication with 30 a suction or air-pump adapted to suck air through said air-exhausting conduits for the air-exhaustion of the cops.

The pump employed for the air-exhaustion may be the identical pump employed in connection with the liquid-exhausting conduit. 40

Each one of the foregoing four chambers is distinct from and unconnected with any one of the other three, and all of said chambers are as stated, in effect, sunken depressions, recesses, or depressed compartments in, or in fact openings through, the front face of the carrier body between its peripheral edge and its center.

The boundaries or divisions between the foregoing chambers are the unchambered or unrecessed portions of the level front face of the carrier body, against which face the cop carrier is mounted for its vibratory movement.

As this machine as shown in the drawings, 55 is not constructed to embody a dead face proper, that is to say a dead face area strictly as such, the solitary function of which it is to be simply a fixed blank surface, open space, or open or closed blank chamber, formed upon 60 or embodied in the carrier body, and so located as to act in connection with cops above the level of the liquid in the tank to permit of their being replaced by other cops,—it is proper to explain that, in this machine, I employ the mouth of the liquid-exhausting conduit to fulfill the functions of Graemiger's dead

face *per se*, and for such purpose to operate in connection with the cop carrier, it being manifestly apparent that it is possible to perform the operation of substituting fresh or untreated 70 cops for charged and liquid-exhausted cops, while a wing orifice registers over the mouth of the liquid-exhausting conduit, and even while the pump in exterior communication with said conduit is in action, as the continued 75 operation of said pump cannot prevent the operation of substitution.

F is a transversely extending dye-slot channeled out of the front face of the carrier body between the air-exhausting chambers and the 80 charging chamber. This slot, which in the mounting of the carrier body, lies considerably below the level of the liquid, is open at its peripheral extremities so as to be constantly full of the liquid in the tank, which serves as 85 a liquid packing between the charging and the air-exhausting chambers and between the charging and the liquid-exhausting chambers. This slot is of especial importance in the operation of dyeing with indigo white solution, 90 and serves as a safeguard to prevent suction of air by the charging pump when employed as a suction device,—which is its preferable employment,—from the air-exhausting or the liquid-exhausting chambers into the charging 95 chamber. Of course, if it were possible to maintain under continuing wear a perfect fit of the cop carrier upon the carrier body, that is to say a fit so close that no air could get between them, this slot would not be important; 100 but as in practice, even with the best construction and most careful adjustment to compensate for wear, interspaces do come to exist between the body and the carrier, this slot, containing, as it does, liquid packing, becomes of 105 importance as a safeguard to the charging chamber in the practice of indigo dyeing, in which operation it is essential to prevent the suction of the charging pump from sucking air, through the interspaces between the body 110 and the carrier, from the liquid-exhausting and air-exhausting chambers into the charging chamber, with the result of oxidizing the indigo, depositing the insoluble indigotine, clogging the fibers of the cops, and preventing the 115 effectual circulation of the dye-stuff through said cops. In other words, in indigo dyeing, this slot opens a free passage for the white indigo solution in the tank to permeate through the crevices or interspaces between the carrier and the body, into the charging chamber, and by its presence to fill said interspaces and exclude the entrance or passage of air. This slot is also of advantage, in that, as there is always, when the exhausting pump is used as a 125 suction device, a rarefied condition or vacuum pressure in the liquid-exhausting chamber and interspaces between the carrier and the body in the area between the charging and liquid-exhausting chambers, its absence would permit of the drawing of the dye-stuff from the charging chamber into the liquid-exhausting

120
130

chamber, a thing undesirable in practice. This slot is but a modified form of the dye-slots set forth and claimed in Graemiger's application for patent referred to.

Having now described the construction of the carrier-body, and how that it is a convenient device for the purpose of conveniently presenting to given perforations of the cop carrier the terminal portion or mouth of the charging conduit, the terminal portion or mouth of the liquid-exhausting conduit, and the terminal portion or mouth of the air-exhausting conduit,—and a device, moreover, with reference to which the carrier is conveniently arranged to oscillate, vibrate, or rock,—C is the cop carrier, composed essentially of a central portion or hub axially apertured to fit it upon the gudgeon b^x of the carrier body, and preferably provided with a pair of oppositely projected hollow radial extensions or wings c^x of any preferred form, but conveniently of that represented in Figs. 1, 2, 3, and 5, which possess a considerable face area, and are as to said area provided with perforations c passing through from said face into their hollow interiors, the office of which is to permit the passage of impregnating liquid or exhausting fluid to or from cops C^x applied to the exterior face of said wings of the carrier and as to their hollow cores in communication with said perforations.

The perforations may be of any desired form. Those shown are simply holes c through the cop carrier which are conveniently externally threaded to receive hollow nipples, fitted to receive removable perforated injection tubes H thrust through cops, and conveniently of a construction invented by me and constituting the subject-matter of an application for patent filed by me February 8, 1887, as Serial No. 226,909. Instead, however, of employing these nipples the injection tubes, or the cops themselves, may be adapted to be fitted directly to the perforations.

The hollow wings, being but portions of the carrier proper, may assume any desired form, they being conveniently, however, of the flat form represented in Figs. 1, 2, 3, and 5, and erected edgewise from the extremities of hollow wing tubes e, which serve not only as supporting devices but also as contrivances by the aid of which the hollow interiors of the wings are placed in communication with outlets, inner-openings, or, as I term them, wing orifices c^a, which open through the rear face of the hub of the cop carrier as shown in Fig. 5, and are in line upon opposite sides of the diameter of said hub. The diametric distance apart of these wing orifices exactly corresponds to the radial distance apart of the two air-exhausting chambers, and also to the radial distance apart of diagonally opposite extremities of the oblong slots which form the respective charging and liquid-exhausting chambers.

The cop carrier is maintained against the face of the carrier body conveniently by means

of a nut b^o applied to the threaded extremity of the gudgeon b^x; and the rear face of the hub of said carrier being conformed exactly to fit the front face of the carrier body snugly within its flanged rim, it is apparent that the cop carrier as an entirety can be vibrated with respect to said carrier body so as to cause the presentation of its wing orifices to the chambers or conduit mouths in said carrier body, as hereinafter fully set forth.

It is apparent that instead of forming the gudgeon upon the carrier body and the aperture therefor in the cop carrier, the cop carrier may be formed with a gudgeon projecting from its inside face and adapted to a cylindrical aperture, or hub, so to speak, formed within the carrier body. It is also apparent that the cop carrier may be formed to surround the carrier body being mounted upon its peripheral surface.

I am screens applied to both extremities of the wings of the cop carrier, as shown in Figs. 1, 2, and 3, in such manner as to have forward projection exceeding that of the applied cops. These screens are preferably formed with angular or beveled faces, and they serve to take up and collect or put aside the scum accumulating on the surface of the liquid in the tank, and thus to keep it off of the cops both as the latter are immersed in and as they emerge from the liquid. These screens as applied to a cop carrier are the invention of the aforesaid August Graemiger.

Vibration, rocking, or oscillation may be imparted to the cop carrier in any convenient manner. A good way is to provide the carrier with a hand lever J, Fig. 2, by the simple movement of which from side to side, and until, for instance, it encounters a rest j, one of which is applied to each side of the tank, as shown in Figs. 1 and 2,—the cop carrier can be vibrated to the limit of its desired throw in either direction.

I do not, of course, restrict myself to the employment of the lever referred to, but contemplate imparting movement to the carrier by any suitable contrivance, as, for instance, by the application of a crank-provided pinion adapted to engage with a circular rack applied to the cop carrier.

Such being a description of a preferred form of apparatus embodying my invention, its operation may be described as follows:—Assuming the pumps operated as suction devices, the following is a description of the operation of my improved apparatus in carrying out the process of charging, impregnation or saturation, liquid-exhaustion, and substitution of charged and liquid-exhausted cops for fresh or untreated cops to be charged and liquid-exhausted,—an operation itself a type of all the others. The desired liquid is introduced into the tank to about the level represented in Figs. 2 and 3, that is to say to a level considerably above the level of the dye slot F, and also sufficiently above that of the air-exhaust-

ing chambers to permit of the complete immersion of all of the cops of a given carrier wing, when the wing orifice of said wing is in registry with the air-exhausting chamber in connection with which said wing orifice operates. The charging pump is conveniently provided with a return pipe so as to return to the tank as much of the liquid employed as is not absorbed by or does not remain in the cops, the liquid being thereby in constant circulation from the tank to the pump and from the pump back to the tank or vice versa. In other words, a constant circulation takes place through both the charging pump and the cops, and the liquid in the tank is reduced only by such quantity of liquids as remains in the cops. The reduction, however, when carried to an extent affecting the normal level of the supply of dye-stuff to the tank, is to be compensated for and the level maintained by fresh supplies. The machine, being supposed unprovided with cops, the carrier is vibrated until one of its wings is raised and the other lowered to the full limit of their respective oscillatory throws, or until said wings relatively occupy the positions represented respectively in Figs. 1, 2 and 3. The perforations of the wing of the cop carrier which has been raised, being, therefore, above the level of the liquid in the tank, and the wing orifice of said wing being in registry with one extremity of the liquid exhausting chamber, as shown in Fig. 2,—a cop is by an attendant supplied to each of the aforesaid perforations, and the said carrier is then, by the operation of the hand lever, caused to descend to the full limit of its path of movement, that is to a sufficient distance to occasion the complete immersion of the group of cops so applied and the presentation of the wing orifice of the carrier wing to which they are applied to the charging chamber. The pump in connection with said charging chamber being, as is preferred, in operation as a suction pump, thereupon through the aforesaid charging conduit, charging chamber, wing orifice, wing tube, and perforations of the carrier wing in question, sucks enough of the liquid contained in the tank through the substance of each of the cops to occasion the saturation of the complete impregnation with said liquid of the threads composing each of said cops. While the charging pump is acting upon the immersed group of cops referred to, the other wing of the cop carrier will be above the level of the liquid in the tank, its wing orifice will be in registry with the liquid-exhausting chamber, and the attendant will be supplying to the perforations of said elevated wing a set of fresh or untreated cops to be charged. So soon as he has done this, a reverse deflection of the hand lever will occasion the reverse vibration or oscillation of the cop carrier as an entirety, the descent and immersion of the wing carrying the unimpregnated cops, applied while said wing was above the level of the liquid, and the registry of its

wing orifice with the charging chamber,—and also the simultaneous ascent of the carrier wing first considered with its charged cops, until its wing orifice registers a second time with the liquid-exhausting chamber, so that the said charged cops are subjected to the action of the pump in connection with said liquid-exhausting chamber so as to be liquid-exhausted of such surplus liquid as they contain at the time of their emergence from the liquid in the tank. So soon as this operation of liquid-exhaustion has been performed upon them, the charged and liquid-exhausted cops of the wing first considered are removed by an attendant and their places supplied by fresh or untreated cops; after which a further re-reverse deflection of the hand lever will occasion the second descent of the wing first considered with its newly applied group of untreated cops, and the first ascent of the wing second considered with its charged cops until the latter are above the level of the liquid, and until the wing orifice of the wing to which they are applied is in registry with the liquid-exhausting chamber so that the cops may be liquid-exhausted, after which they are removed and a further group of fresh or untreated cops applied to said second wing which is then by a redeflection of the hand lever actuated to its second descent.

A continuance more or less rapid of the foregoing operation constitutes a practice of that process of which liquid-exhaustion, impregnation, and substitution, are the steps, and which, as an entirety, is perhaps the most important process which my machine is adapted to effectuate.

In considering the foregoing movement it will be observed that each wing orifice operates in connection with a corresponding or adjacent extremity of both the charging and the liquid-exhausting chambers. Thus, the orifice of the left hand wing of Fig. 2 operates in connection with the left hand extremity of both the charging and the liquid-exhausting chambers, while the orifice of the right hand wing similarly operates in connection with the right hand extremities of said respective chambers.

In the rocking of the carrier, it will also be observed, that its wing orifices respectively sweep past the respective air-exhausting chambers, the left hand orifice passing both in its upward and downward movement into and out of registry with the left hand air-exhausting chamber E², while the right hand wing orifice performs a similar movement with respect to the right hand air-exhausting chamber E³.

When liquid-exhaustion is not desired, or is intended to be performed in a separate machine, the liquid-exhausting chamber is cut off, and the liquid exhausting pump or pumps thrown out of action; whereupon the above described operation becomes simply an operation of charging and cop-replacing.

I prefer, as stated, to conduct the foregoing operation by sucking both the charging liquid and then the surplus liquid from the outer surfaces of the cops inward, but it is obvious that the same result can be secured by forcing impregnating liquid and liquid-exhausting fluid from the core of the cops outwardly to their surfaces. I prefer, also, to use pumps, strictly as such, to force or suck the liquids and fluids utilized, but any other forcing or liquid-exhausting devices may be employed in the stead of pumps, and I therefore herein use the word pump generically.

When easily oxidizable liquid dies, such as indigo white solution, are employed in indigo dyeing, it is important to keep air out of the solution to prevent its combining with the white indigo to form insoluble indigotine, and therefore it is of advantage to extract or exhaust the air from the cops before subjecting them to the action of the charging conduit; because otherwise, the insoluble indigotine being sucked or forced into the cops by the action of the charging pump, would clog their fibers and prevent the proper circulation of the dye-stuff through said cops in the operation of charging proper. This I conveniently accomplish by the aid of the air-exhausting chambers E² E³ and their pump referred to,—the wing orifices of the respective wings coming, in their path of movement, respectively into and out of registry with said chambers as the carrier is caused to vibrate to occasion the complete immersion first of one wing with its applied cops and then of the other,—the said cops being thereby subjected to the action of the air-exhausting pump both as they descend into the liquid in the tank and as they ascend from out it. This subjection to such action as the cops descend, occurs before the cops of the wing descending are subjected to the action of the charging pump, by the registry of the orifice of the wing to which they are applied with said charging chamber.

The importance of the air-exhaustion is only as the untreated cops are descending to be charged, and its action upon the charged cops is of no moment, it being only, in effect, an action of liquid-exhaustion to a very slight degree,—as, of course, the wing orifices are but for a very short time in registry with the respective air-exhausting chambers.

It will be apparent that in conducting the foregoing operating of air exhaustion the cops will become more or less filled with the indigo solution. The period during which a given wing orifice presents over its air-exhausting chamber is, however, in the movement of the carrier, so limited that no impregnation saturation or charging proper, in the sense of a thorough circulation of liquids through the cops, takes place; and the operation of air exhaustion is not, therefore, one of charging or saturation in the sense in which those terms are, in this specification, employed as applied to the operations conducted through the me-

dium of the charging chamber by the action of the charging pump. Such of the dye-stuff, moreover, as is, by the operation of the air-exhausting pump, drawn through the cops and into the air-exhausting chambers, and as has become oxidized, is not, as is apparent, admitted into the tank at all, but is drawn off to the air-exhausting pump, from which, in practice, it is discharged into a special vessel and deoxidized before being again supplied to the tank.

The air-exhausting chambers may be employed either with or without the liquid-exhausting chamber.

In order to employ my apparatus for scouring, bleaching, steaming, mordanting, or washing yarn in cops, it is apparent that it will be only necessary to supply the desired bleaching or other selected liquid to the tank and charging pump, and to repeat in connection with such liquid the operation already described.

If desired, the liquid-exhausting pump can be replaced by an injector or kindred device employed to inject steam through the cops, or the apparatus being placed in a hot chamber the liquid-exhausting pump may be used to exhaust or draw hot air through them.

Such being a description of a preferred form of apparatus adapted to effectuate my invention, it will be apparent that it is adapted for the practice of any one of the five processes invented by Graemiger, to which I have hereinbefore referred. Thus, by throwing the pump or pumps operating in connection with the air-exhausting and the liquid-exhausting conduits, entirely out of action, the process of dyeing, scouring, bleaching, or otherwise treating the cops by impregnation of a selected liquid, and of replacing the impregnated cops with others to be impregnated,—can be practiced. Thus, again, by shutting off the air-exhausting chambers from communication with their pump, the operation of charging or saturation with liquid, liquid-exhausting, and substitution of, or replacing, the cops, can be performed. It is to be remarked that the foregoing operation can, in fact, be performed without discontinuing the operation of air-exhaustion, inasmuch as the said operation, although inert for useful purposes in any operation except that of indigo dyeing, is harmless in any other operation involving saturation. Thus, again, by throwing the charging pump out of operation or by shutting off the charging conduit from communication with said pump, and by removing all liquid from the tank, which in such case becomes simply a fixed supporting frame-work, the operation of liquid-exhausting cops which have been in any other machine impregnated with the desired liquid, and of replacing said liquid-exhausted cops with fresh cops to be liquid-exhausted, can be performed. Thus, again, by shutting off the liquid-exhausting chamber from communication with the liquid-exhausting pump, the op-

eration of air-exhaustion, impregnation, and substitution of cops can be performed. Thus, finally, all of the conduits being in communication with their respective pumps, either the 5 operation of air-exhaustion, impregnation, liquid-exhaustion, and substitution of cops; or, the liquid-exhausting pump being out of action, the foregoing operation, omitting the 10 step of liquid-exhaustion, can be performed either with readily oxidizable liquid dye stuffs in the operation of dyeing, or with any desired liquid in any selected operation involving saturation of the cops.

The best results are obtained by employing 15 both the liquid-exhausting and the charging pumps as suction pumps, and by operating an independent pump (although the liquid-exhausting pump may be used) as a suction pump to perform, when desired, the work of air-exhaustion.

In Figs. 6, 7, 8, 9, and 10, of the drawings I have represented a machine embodying the same essential features of construction and operation as the machine above described,—the 25 difference being essentially in the direction of application of the wings to the cop carrier,—the said wings being applied flatwise, or in a plane parallel with the plane of an extended diameter of the cop carrier longitudinally bisecting said wings, as opposed to being applied edgewise as in the case of the machine first represented and described. The construction that I have first described is however such as I prefer, although it is apparent that a skillful mechanic can greatly modify the special form, construction, and special relative arrangement of the essential elements of my invention, namely, the tank, the vibratory cop carrier, the carrier body, and the various conduits,—my invention being broad enough to comprehend other applications of a vibratory or oscillatory cop carrier with respect to a fixed tank and the mouths or terminal portions of conduits such as are set forth. Thus, 40 again, while it is essential, when charging, either alone or in connection with other operations, is a step of the process for the time being under practice, that a charging conduit should act to conduct liquids to or from given 45 wing orifices of the cop carrier, in communication, as stated, with given cops,—and that a liquid-exhausting conduit, when liquid-exhaustion, either alone or in connection with charging, is a step of the process for the time 50 under practice, should similarly act to conduct air to or from given cops,—it is immaterial through the medium of what form of discharging orifice, mouth, or other aperture adapted to register or align itself for the time 55 being with said wing orifices, such conduit or conduits do so act. Thus, finally, while I prefer to apply the cops to the cop carrier by applying them to extensions, or "wings" as I call them, supported from the central hub portion of the carrier proper, it is apparent that 60 they may be otherwise applied. The wings

are simply convenient devices the use of which avoids so low a level of liquid in the tank as would be imperative were the cops applied closer to the axis of the carrier; and they are, 70 moreover, contrivances of such character that, if desired, they may be made bodily removable for the application and removal of the cops or for repairs, and such as to also afford a greater surface area for perforations and permit of a reduction in thickness of the carrier proper and carrier body. As stated, however, the wings may assume various forms, it being of the gist of the invention, however, that they should be hollow or chambered integral 80 portions of the carrier perforated for the application of the cops, and in communication each as to its hollow interiors with a wing orifice formed in the central portion of the carrier proper and adapted to register with the 85 conduit mouths.

It is proper for me to state that I do not broadly claim a flat or disk-like carrier body against the face of which a correspondingly flat or disk-like cop carrier, having perforations directly through it, rotates, as such special construction is of the invention of the said Graemiger.

Having thus described my invention, I claim and desire to secure by Letters Patent:—

1. In an apparatus of the class herein recited, in combination,—a cop carrier adapted to be vibrated, oscillated, or rocked,—a fixed carrier body with reference to which the cop carrier has movement,—and suitable means 100 for imparting to said carrier a vibratory, oscillatory, or rocking movement referably to said carrier body,—substantially as set forth.

2. In an apparatus of the class herein recited, the combination,—of a cop carrier which is provided with oppositely applied hollow wings or extensions, and which is adapted to be vibrated, oscillated or rocked,—a carrier body containing or embodying the mouths of fixed conduits, referably to which the carrier 110 is adapted to be vibrated, oscillated, or rocked,—a tank or frame-work referably to which the carrier body and conduits are fixed,—and means for vibrating, oscillating, or rocking the carrier,—substantially as and 115 for the purposes set forth.

3. In a machine of the class herein recited, the combination,—of a cop carrier to which are applied two diametrically opposite groups of cops, and which is adapted to be vibrated, 120 oscillated, or rocked,—a carrier body with reference to which the cop carrier vibrates, oscillates, or rocks, and which contains or embodies diametrically opposite mouths of conduits which are in exterior communication 125 with suction or pressure pumps,—a tank or frame-work referably to which the carrier body and the conduits are fixed,—and means for vibrating, oscillating, or rocking the carrier,—substantially as and for the purposes 130 set forth.

4. In an apparatus of the class herein re-

cited, in combination,—a cop carrier adapted to be vibrated, oscillated, or rocked,—and having opposite hollow wings the hollow interiors of which lead to wing orifices and are 5 perforated for the application of cops,—a carrier body containing or embodying oppositely disposed mouths of fixed conduits over which mouths the orifices of the wing are caused to alternately present as the carrier is caused to 10 rock,—a tank or frame-work referably to which the carrier body and conduits are fixed,—and means for rocking vibrating or oscillating the carrier,—substantially as set forth.

15 5. In an apparatus of the class herein recited, in combination,—a cop carrier adapted to be vibrated, oscillated, or rocked, and having opposite hollow wings the hollow interiors of which lead to wing orifices and are perforated 20 for the application of cops,—a fixed carrier body containing or embodying the oppositely disposed mouths of a charging conduit and a liquid-exhausting conduit over which mouths the wing orifices of the cop carrier are alternately and oppositely presented as the carrier 25 is caused to oscillate,—a tank or frame-work referably to which the carrier body and conduits are fixed,—and means for vibrating oscillating or rocking the cop carrier, substantially as set forth.

30 6. In an apparatus of the class herein recited, in combination,—a cop carrier adapted to be vibrated, oscillated, or rocked, and having opposite hollow wings the hollow interiors of which lead to wing orifices and are perforated 35 for the application of cops,—a fixed carrier body containing or embodying the oppositely disposed mouths of a charging conduit and a liquid-exhausting conduit, and also the oppositely disposed mouths of air-exhausting conduits, over all of which mouths the wing orifices of the cop carrier are alternately and oppositely presented as the carrier is caused to 40 oscillate,—a tank or frame-work referably to 45 which the carrier body and conduits are

fixed,—and means for vibrating oscillating, or rocking the cop carrier,—substantially as set forth.

7. In an apparatus of the class herein recited, in combination,—a cop carrier composed of a 50 central disk-like portion and radial hollow wings or extensions provided with perforations, and in communication with wing orifices in said central portion,—a flat or disk-like carrier body against which the carrier 55 vibrates, which is as to its face in contact with the central portion of the cop carrier through which the wing orifices open, and which contains or embodies the oppositely disposed mouths of fixed conduits over which 60 said wing orifices of the carrier are caused to alternately present as the carrier is caused to vibrate,—a tank or frame-work referably to which the carrier body and conduits are fixed,—and means for vibrating, oscillating, 65 or rocking the carrier,—substantially as set forth.

8. In a machine of the class above recited, a carrier body the working face of which is a plane containing or embodying two oblong 70 conduit mouths parallel and diametrically opposite at equal radial distances apart, substantially as set forth.

9. In a machine of the class above recited, a carrier body the working face of which is a 75 plane containing or embodying two oblong conduit mouths parallel and diametrically opposite at equal radial distances apart, and two similar, and preferably circular, conduit mouths similarly disposed with reference to 80 each other and respectively intermediate between the oblong conduit mouths aforesaid, substantially as set forth.

In testimony whereof I have hereunto signed my name this 18th day of August, A. D. 1887.

HOWARD RICHMOND.

In presence of—

GILMAN E. JOFF,
G. RICHMOND PARSONS.
